UNITED STATES PATENT OFFICE

FREDERICK JOHN HUMPHREY, OF ILFORD, ENGLAND, ASSIGNOR TO ARMAFLEX PARENT, LIMITED, OF LONDON, ENGLAND, A BRITISH COMPANY

CABLE MAKING AND LIKE MACHINE

Application filed January 2, 1930, Serial No. 418,080, and in Great Britain January 21, 1929.

This invention is for improvements in or relating to cable-making and like machines of the type in which a flexible metallic cover or armouring is applied to a core which may 5 be an insulated wire or wires or any other flexible article.

In machines of this type as hitherto known, the core has been fed through a rotating hollow mandrel, being supplied thereto from a 10 reel or reels which were rotated bodily with the mandrel. The strip material which constituted the armouring was passed through forming-rollers which imparted the desired interlocking shape to it, like the well-known 15 flexible metallic tubing, and was then laid on the exterior of the mandrel from which, whilst encircling the core, it was drawn off by a suitably mounted and bodily rotated drum. After leaving the mandrel and before 20 being wound on to the drum, the assembled cable was passed through a tapering gauge which compressed the armouring upon the core so as to grip it and prevent relative lengthwise movement between the core and 25 the armouring. The reel or reels and the drum aforesaid are rotated bodily at the same speed so that theoretically no twisting of the core should occur.

It is found in practice that difficulties arise 30 in the operation of these machines, due, it is believed, to variations in the hardness or uniformity of the armouring strip; it will be appreciated that the rate of feed of the core, and of the armouring strip, must be exactly 35 proportional to the rate at which the completed article is withdrawn, but the last-mentioned rate is influenced by the passage of the cable through the tapering gauge which compresses the armouring on to the core, and 40 any irregularities, for example, in the hardness of the armouring strip, which changes the rate at which it can be compressed on the core interferes with the production of a satisfactory finished product. An object of this 45 invention is to provide certain modifications in the constructional details of the machines whereby these difficulties are obviated.

According to the first feature of this invention, the reel or reels which carry the core and supply it to the rotating hollow mandrel

are not carried by the same shaft as the mandrel but are connected thereto through a clutch or equivalent device which can be caused to slip. Preferably the clutch is controlled by the operator so that he can at will 55 reduce the rate at which the core is revolved, in order to maintain it at the correct speed relatively to the laying-on and compressing of the armouring.

If the core is a simple insulated cable and 60 twisting occurs, the insulation is liable to become damaged and the cable thereby rendered useless. Further, if the core comprises two or more strands, twisting together of these strands shortens the length of the cable 65 which results in a dead loss of cable because such twisting is unnecessary. The provision of the aforesaid clutch enables these disadvantages to be obviated.

In the machines hitherto used, the tapering 70 gauge by which the armouring is compressed upon the core was formed with a smooth interior surface, and according to another feature of this invention the inner surface of the gauge which operates upon the armouring 75 whilst having the same general tapering shape is provided with a helical groove which is so shaped as to conform with the external shaping of the armouring when laid in place on the core. The successive convolutions of 80 the armouring are thereby maintained in their correct relative spacing one with another whilst being compressed upon the core, so that a more satisfactory product is ensured.

According to yet another feature of this 85 invention there may be provided between the mandrel and the compressing gauge, a plurality of relatively soft pads which are arranged to press upon the armouring before it enters the gauge. These pads remove any 90 excess oil from the outer surface of the armouring and exert a slight preliminary compressing action thereon. If the machine is working normally, this preliminary compression is almost negligible, but in the event of a portion of the armouring being harder than 95 normal, it does not receive its correct formation whilst on the mandrel and leaves the mandrel with its convolutions of too large a diameter. These pads will engage and exert 100

a greater pressure under these circumstances, and therefore facilitate the action of the final compressing gauge.

In the accompanying drawing, which illustrates the invention applied to a machine of the type set forth for armouring electric cables by a flexible metallic tubular covering—

Figure 1 is a side elevation of the machine,
10 Figure 2 is a sectional view of the compressing gauge,

Figure 3 is a sectional view of the soft pads for preliminarily compressing the armouring, and

15 Figure 4 is a perspective view thereof.

Like reference numerals indicate like parts in the various figures of the drawing which are diagrammatic.

The machine comprises a suitable frame indicated generally by the reference numeral 10, wherein there is mounted a hollow shaft 11. The said shaft is driven by means of gear wheels 12, 13 from fast and loose pulleys 14 mounted on a shaft 15. Secured to one end 20 of the shaft 11 is a hollow mandrel indicated generally by the reference numeral 16. The end of said mandrel remote from the shaft 11 is reduced in external diameter as shown at 25 17.

30 At the other end of the shaft 11 and in alignment therewith, there is arranged a shaft 18 which is rotatably mounted in bearings carried by standards 19, 20 forming part of the frame 10. Mounted on the shaft 18 to 35 rotate therewith is a frame 21 carrying two reels 22 on which the two wires 23 forming the core that is to be armoured are stored. The end of the shaft 18 which is mounted in the standard 19 is recessed to accommodate 40 the wires 23 which are led through the interior of the shaft 11 and mandrel 16.

A second frame 24 carries a drum 25 which is mounted in a rotatable frame 26 for the purpose of receiving the armoured cable after 45 it has been completed. Any suitable construction of drum which rotates bodily whilst winding up the cable may be used, such constructions being well known in the art. The drum 25 and the mechanism appertaining thereto may be driven in any convenient manner from a shaft 27. For instance, in the arrangement shown in Figure 1, a shaft 28 in alignment with the shaft 11 may be driven from the shaft 27 by chain gear 29. Mounted 50 on the shaft 28 is a gear wheel 30 which meshes with a gear wheel 31 on a shaft 32 rotatably mounted in bearings 33 on the rotatable frame 26. The shaft 32 carries a bevel wheel 34 which gears with a bevel wheel 35 frictionally 55 coupled to the drum 25 in the usual manner.

On a standard 36 forming part of the frame 24 there is mounted a tapering gauge 37 which is aligned with and faces the mandrel 16. The frame 10 carries upon suitable supports, dies or rollers (not shown on the draw-

ing as they are well known in the art) for imparting to a flat strip of the material which forms the armouring of the cable, the desired profile whereby successive turns of it interlock with one another. Also mounted on the frame 10 is a rotatable drum 38 which is driven from the fast and loose pulleys 14 by means of a gear wheel 39 on the shaft 15 which meshes with a gear wheel 40 on a shaft 41. A second gear wheel 42 on the shaft 41 meshes with a gear wheel 43 on a shaft 44 on which the drum 38 is mounted. The function of the drum 38 is to draw the armour strip through the forming dies or rollers aforesaid.

The mechanism hereinbefore described is well known and it is thought unnecessary to describe its operation in detail. Suffice it to say that the two wires 23 which constitute the core are led from the reels 22 through the hollow shaft 11 and the hollow mandrel 16. The armouring material which is initially in the form of a flat strip is led between the forming dies or rollers aforesaid, around the drum 38 and thence on to the reduced part 17 of the mandrel. The armouring is then pressed closely on to the mandrel by suitable pressing means, one of which is indicated at 45.

The core and the armouring surrounding it then pass into the open end of the gauge 37 and are drawn therethrough by the drum 25. It will be understood that the frames 21 and 26 are rotated at the same speed so that theoretically no twisting together of the wires 23 should occur, but in practice for the reasons hereinbefore stated twisting is liable to occur. In order to avoid this twisting a slipping clutch is provided according to the invention in the drive to the frame 21.

The shaft 18 on which the reels 22 are mounted, is driven from the shaft 11 by means of chain gearing 46 between the shafts 11 and 27 and a chain gear 47 between the shaft 18 and a shaft 48 which is operatively connected to the shaft 27 by a slipping clutch 49. The said clutch is arranged to be operated by a foot pedal 50 acting through links 51 connecting it to the usual forked clutch lever 52. Thus it will be seen that by means of the clutch 49 the operator can at will reduce the rate at which the reels 22 are bodily rotated so as to maintain the correct speed of location of the core relatively to the laying-on and compressing of the armouring.

The gauge 37 has as usual a tapered bore, but instead of being plain as heretofore, said bore is provided with a helical groove 53 as shown on an enlarged scale in Figure 2. This groove conforms with the external shaping of the armouring when led upon the core and thus ensures the production of a more satisfactory article as hereinbefore explained.

Mounted between the mandrel 16 and the

gauge 37 and supported by a bracket 54 on the standard 36, is a device comprising two relatively soft pads 55, see Figures 3 and 4, which are provided for the purpose hereinbefore set forth and are arranged to press upon the armouring before it enters the gauge 37. These pads are secured to plates 56 arranged to be adjusted nearer together or farther apart by means of a right-and-left-hand screw 57. A stationary guide rod 58 is provided to prevent tilting of the pads 55 and plates 56.

It has been found that a machine embodying the modifications hereinbefore described obviates the difficulties hitherto encountered in the armouring of wires and like flexible cores by a flexible metallic tube armouring.

I claim:

1. A cable-making or like machine of the type set forth, comprising in combination a hollow mandrel, means for rotating said mandrel, a reel to receive a supply of material constituting the core, means for rotating said reel bodily about the axis of the mandrel, means for feeding the core through the mandrel, means for feeding a shaped strip of armouring material on to the mandrel, a take-up device for drawing the armouring material off said mandrel whilst encircling the core, means for bodily rotating the take-up device, which reel and take-up device are rotated at the same speed, a device for compressing the armouring upon the core after it leaves the mandrel, and a plurality of relatively soft pads which are arranged to press upon the armouring before it enters said device, for the purpose described.

2. A cable-making or like machine of the type set forth, comprising in combination a hollow mandrel, means for rotating said mandrel, a reel to receive a supply of material constituting the core, means for rotating said reel bodily about the axis of the mandrel, means for feeding the core through the mandrel, means for feeding a shaped strip of armouring material on to the mandrel, a take-up device for drawing the armouring material off said mandrel whilst encircling the core, means for bodily rotating the take-up device, which reel and take-up device are rotated at the same speed, a device for compressing the armouring upon the core after it leaves the mandrel, a plurality of adjustably mounted soft pads arranged to press upon the armouring before it enters said device, and means for adjusting said pads towards and away from one another.

3. A cable-making or like machine of the type set forth, comprising in combination a hollow mandrel carried by a hollow shaft, means for rotating said hollow shaft, a shaft in alignment with said hollow shaft and carrying a frame on which a reel of core material is mounted, means for driving said shaft from the hollow shaft including a manually

controlled clutch which can be caused to slip, means for feeding the core through said hollow shaft and said mandrel, means for feeding a shaped strip of armouring material on to the mandrel, a take-up device for drawing the armouring material off said mandrel whilst encircling the core, means for bodily rotating the take-up device, which frame-carrying shaft and take-up device are rotated at the same speed, a plurality of soft pads arranged to press upon the armouring for the purpose described after it leaves the mandrel, and a hollow tapering compressing gauge having on its inner surface which operates upon the armouring a helical groove which is shaped to conform with the external shaping of the armouring when laid in place upon the core.

In testimony whereof I affix my signature.

FREDERICK JOHN HUMPHREY.
